DESIGN FOR A SCORING DEVICE FOR PINOCHLE AND OTHER GAMES

Chris A. De Pirro, Chicago, Ill.

Application July 19, 1945, Serial No. 120,809

Term of patent 3½ years

(Cl. D34—5)

To all whom it may concern:

Be it known that I, Chris A. De Pirro, a citizen of the United States of America, residing at 611 South Ada Street, Chicago, Illinois, have invented a new, original, and ornamental Design for a Scoring Device for Pinochle and Other Games, of which the following is a specification, reference being had to the accompanying drawing forming a part hereof.

Referring to the drawing, Fig. 1 is a front elevational view of a scoring device for pinochle and other games embodying my design; Fig. 2 is a top plan view; Fig. 3 is a side edge view and Fig. 4 is a bottom plan view.

I claim:

The ornamental design for a scoring device for pinochle and other games, substantially as shown.

CHRIS A. DE PIRRO.
